UNITED STATES PATENT OFFICE.

JOB M. ROBERTS, OF PANA, ILLINOIS.

CHECK-ROWER FOR CORN-PLANTERS.

SPECIFICATION forming part of Letters Patent No. 283,817, dated August 28, 1883.

Application filed April 23, 1883. (No model.)

To all whom it may concern:

Be it known that I, JOB M. ROBERTS, a resident of Pana, in the county of Christian and State of Illinois, have invented certain new and useful Improvements in Check-Rowers for Corn-Planters, of which the following is a full, clear, and exact specification.

My invention relates to that class of check-rowers which are operated by a smooth cord, which is stretched across the field and anchored; and my invention consists in the device used to convert the continuous resistance of said cord against the motion of the planter into reciprocating motion in the seed-slides thereof.

My invention also consists in the device used to neutralize the jar in the drop when the stroke of the check-rower is longer than the stroke of the seed-slide.

In the drawings accompanying and forming a part of this specification, *a* is a cylinder, rigid on its shaft, and provided with deflected groove *g* in its circumference.

b is a V-grooved pulley that works loosely on the shaft of the cylinder, and over which the cord passes.

c is a lever, provided with a suitable arm or projection, *d*, that engages a groove in a shoulder of the pulley *b*.

e e are guide-pulleys that hold the cord in position on the main pulley.

f f are uprights that are detachably secured to bar *m*, and in which cylinder *a* and pulley *b* are supported.

h i h i are receiving and discharging pulleys for cord *n*.

o is a horizontal projection from the check-row bar that forms a pivotal support for lever *p*.

r is the rod that connects the seed-slide *q* with lever *p*.

s t is the device used to neutralize the jar of the stroke, and *u* is a projection of suitable form to engage cylinder *a*.

Figure 1 is a plan of my device. Fig. 2 is an elevation of the central portion thereof,

showing the cylinder and pulley disconnected and uprights *f f* joined together, as I prefer to make them; and Fig. 3 shows the operation of my jar-neutralizing device.

In operation, pulley *b* is thrown in contact with cylinder *a*, and both pulley and cylinder are continuously rotated by cord *n*. Lever *p* is provided with an anti-friction roller that fits in groove *g*, and by means of which said lever is made to oscillate as the cylinder rotates. The oscillating motion of lever *p* is conveyed to the seed-slide through rod *r*. In case the stroke of lever *p* should be longer than the stroke of the seed-slide, disk *s* will give a partial revolution, as shown in Fig. 3, and the pivot of said disk may be held out of line with rod *r*, and a dead-lock be thereby prevented by projection *t* coming in contact with the spur *z* on the disk *s*. In making a turn at the end of the field pulley *b* is thrown out of contact with cylinder *a* and permitted to rotate loosely on the shaft until the planter is again in proper position, when the connection between said pulley and cylinder is re-established and the dropping effected, as heretofore described. The pulley *b* is made to revolve once while the planter traverses twice the distance between rows, and one revolution produces two complete motions of the seed-slides.

I claim—

1. Cylinder *a*, provided with groove *g*, pulley *b*, provided with a grooved shoulder, and arm *c*, provided with projection *d*, in combination with uprights *f f*, projection *o*, and lever *p*, as and for the purpose set forth.

2. The combination, with pulley *b*, cylinder *a*, and guide-pulleys *e e*, of pulleys *h i h i*, as and for the purpose set forth.

3. The combination of rod *r*, bar *q*, disk *s*, spur *z*, and projection *t*, as and for the purpose set forth.

JOB M. ROBERTS.
